(57) **CLAIM**

We claim the ornamental design for a rotary card holder, as shown and described.

DESCRIPTION

FIG. 1 is a first perspective view of the rotary card holder.
FIG. 2 is a front view of the design.

FIG. 3 is a second perspective view of the design.

FIG. 4 is a third perspective view of the design.

FIG. 5 is a perspective view of the rotary card holder substantially identical to that of FIG. 1, except that the broken line showing of the divider has been removed for clarity; and,

FIG. 6 is a perspective view of the rotary card holder substantially identical to that of FIG. 4, except that the broken line showings of the divider and foot have been removed for clarity.

The broken line showing of the environment is for illustrative purposes only and forms no part of the claimed design.
